(57) CLAIM

The ornamental design for an outdoor mat as shown and described.

DESCRIPTION

FIG. 1 is a perspective view of an outdoor mat in an open configuration, showing our new design;

FIG. 2 is a top plan view of the outdoor mat in the open configuration of FIG. 1;

FIG. 3 is a bottom plan view of the outdoor mat in the open configuration of FIG. 1;

FIG. 4 is a right-side elevation of the outdoor mat in the open configuration of FIG. 1;

FIG. 5 is a left-side elevation view of the outdoor mat in the open configuration of FIG. 1;

FIG. 6 is a front-side elevation view of the outdoor mat in the open configuration of FIG. 1; and

FIG. 7 is a back-side elevation view of the outdoor mat in the open configuration of FIG. 1.

FIG. 8 is a perspective view of the outdoor mat shown in FIG. 1 in a closed configuration.

FIG. 9 is a top plan view of the outdoor mat in the closed configuration of FIG. 8.

FIG. 10 is a bottom plan view of the outdoor mat in the closed configuration of FIG. 8.

FIG. 11 is a right-side elevation of the outdoor mat in the closed configuration of FIG. 8;

FIG. 12 is a left-side elevation view of the outdoor mat in the closed configuration of FIG. 8;

FIG. 13 is a back-side elevation view of the outdoor mat in the closed configuration of FIG. 8; and,

FIG. 14 is a front-side elevation view of the outdoor mat in the closed configuration of FIG. 8.

Any features shown in broken lines in the various figures are for illustrating environmental structure and form no part of the claimed design.

1 Claim, 9 Drawing Sheets
